UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A SPOON, &c.

SPECIFICATION forming part of Design No. 23,717, dated October 23, 1894.

Application filed September 28, 1894. Serial No. 524,403. Term of patent 14 years.

To all whom it may concern:

Be it known that I, WILLIAM C. CODMAN, of Providence, in the county of Providence and State of Rhode Island, have invented and produced a new and original Design for Handles of Spoons and Similar Articles, of which the following is a full, clear, and exact specification, reference being had to the accompanying drawings, forming part thereof.

Figure 1 is a representation of a handle attached to the bowl portion of a spoon and illustrating the obverse of my new design, the tine portion of a fork being shown in dotted lines indicating the use of the handle therewith. Fig. 2 represents a reverse view of the same.

The leading features of my new design consist in the outline of the handle which curving inward from the body of the article to which the handle is attached then extends upward to inwardly curving shoulders, giving an inwardly-inclined effect to this portion of the handle. Above these shoulders the outline extends very gradually outward increasing the width of the handle, the outward curving lines increasing in boldness toward the upper portion and being turned sharply inward to break the flowing line. Again beyond this break the outline curves abruptly outward for a short distance, then curves slightly inward, again boldly outward and inward over the upper end of the handle uniting in a semi-circular combination of short curves. These leading features are further distinguished by the surface ornamentation consisting on the obverse of spreading foliations extending from the base of the handle on to the surface of the article attached thereto, semi-oval scrolls, between and above the foliations, joined at their lower portions by a bead below which is a leaf ornament. Inclosed within the scrolls is a branched figure, the semi-circular scrolls and branched figure filling the parallelogram formed by the parallel sides of the lower portion of the handle, and from the upper displayed ends of the semi-circular scrolls extend curving branches terminating in scrolled ends which overlap the beadings forming borders for the neck of the handle. These beadings begin in leaf-like ends on the handle base and extend up-

ward parallel with the outline of the handle at this portion, their upper ends joining inwardly-overlapping foliations having the appearance of embracing the handle at the 55 wider portion of the neck and finishing in inwardly-turned scrolls which accentuate the sharply indented portions of the outline, the ends of these scrolls meeting in the center of the handle. Thus the scrolls present the appearance of a border surrounding a convex panel on which is displayed a branched ornament having a leaf-like base below which are small inwardly-turned scrolls connected by a bead from which is pendent a stemmed 60 ornament extending on to the neck of the handle. To further accentuate the indentations of the outline are foliated scrolled borders following the outline of the upper portion of the handle overlaid by inwardly-turned leaves, between the upper ends of which borders is located a scalloped shell-like ornament with lobe-like figures in the panels.

The surface ornamentation on the reverse 75 consists of an inverted branched ornament extending on to the surface of the article to which the handle is attached. Extending between the branches of this ornament are stems with leaves on their ends. Above this 80 are the inwardly-scrolled ends of the beaded borders, for the lower edges of the handle, from which leaf-like scrolls extend, and inclosed within these borders is an ornament 85 the branches of which have scrolled ends partially overlapping the beaded borders. The upper ends of these beaded borders meet inwardly overlapping leaves, gradually widening at their upper portions, which are formed by scrolls having inwardly-turned ends embracing a panel on which is displayed a branched ornament. The lower ends of these scrolls are joined by a bead from which a stainen-like ornament depends. The upper ends of the scrolls mark the indentations in 90 the outline of the handle and branched inward from these are foliated scrolls. From these upper ends of the scrolls extend other scrolls forming borders for this portion and having inwardly overlapping leaves. These 95 last scrolls follow the curves of the upper end of the handle and between them is inclosed

a scalloped shell-like figure with concaved panels above which is a convex fluted figure forming the finial of the handle.

In the drawings 5 represents the handle 5 and 6 the bowl of a spoon. It may, however, represent the main portion of any similar article, one of which is indicated in dotted lines. The outline of the handle extends upward from 7-7 in parallel lines to the inwardly-curving shoulders 8-8 to form the base which has the appearance of a parallelogram. From the shoulders 8-8 the outline extends in elongated curves gradually increasing the width of the neck portion of the handle to 9-9 15 where the curves of the outline become bolder curving outward to 10-10 and then sharply inward to form the indentations 11-11. Above this the outline curves sharply outward, then gradually inward to 12-12, then 20 boldly outward to 13-13 and finally inward to 14-14 to meet the semi-circular group of short curves 15 forming the upper end of the handle. Beginning at the base the obverse of the handle is ornamented with the spreading leaves 16-16 which extend on to the bowl portion. On the parallelogram between 7-7 and 8-8 the ornamentation consists of the semi-circular scrolls 17-17 inclosing the branched ornament 18, while from the scrolls 30 17-17 extend the branches 19-19 which overlap the lower foliated ends of the bead borders 20-20. These borders follow the outline of the neck of the handle and are finally merged into the inwardly overlapping leaves 35 21-21, the plain portion of the neck between the bead borders being convex in cross section. From the leaves 21-21 extend the scrolls 22-22 forming borders for the enlargement of the handle at 10-10, their upper ends being turned inward and meeting, thus giving the central portion the appearance of a wholly inclosed heart-shaped panel on which is displayed the branched figure 23 supported on the base 24 from which the stem 40 25 extends down between the leaves 21-21 connecting with the inverted calyx-like figure 26 resting on the convex surface of the neck. From the scrolls 22-22 extend the foliated scrolls 27-27 their junction being at the indentations 11-11 and serving to accentuate 50 the same. These scrolls 27 follow the outline of the upper portion of the handle their ends

being turned inward to the shell-like ornament 28 with convex or lobe-like panels and with the upward concave extension 29. 55

On the reverse the surface ornamentation consists of the inverted branched ornament 30 which extends on to the body of the article to which the handle is attached. Among the branches of the ornament are stems having leaves at their ends. The parallelogram between 7-7 and 8-8 has bead-borders 31-31 the lower ends of which are scrolled inward and from these borders extend the leaves 32-32. Between the borders is located a branched figure 33 the scrolled ends of which partially overlap the borders. Above this the borders 31 curve inward at the shoulders 8-8 and follow the outline of the neck to the inwardly overlapping leaves 34-34 70 which finish at their upper ends in the scrolls 35-35 having inwardly-turned ends which give a panel effect to this portion of the handle, the upper ends serving to accentuate the indentations 11-11. Between the scrolls 35 75 is the branched figure 36 below which is the pendent ornament 37. From the upper ends of the scrolls 35-35 extend inward and upward the foliated scrolled ornament 38, and partially overlapped by these ends of the scrolls 35 are the foliated scrolled borders 39-39 which, following the outline of the handle at this portion, curve over the top of the same and embrace the shell-like ornament 40 having concave panels and a convex fluted finial which accentuates the group of short curves 15.

What I claim is—

1. In the design for the handle of a spoon or similar article, the obverse as herein shown 90 and described.

2. In the design for the handle of a spoon or similar article, the reverse as herein shown and described.

3. The design for handles of spoons and 95 similar articles as herein shown and described.

In witness whereof I have hereunto set my hand.

WILLIAM C. CODMAN.
